(57) **CLAIM**

The ornamental design for a laundry bin, as shown.

DESCRIPTION

FIG. 1 shows a top left side perspective view of a laundry bin showing my new design;

FIG. 2 shows a top plan view thereof;

FIG. 3 shows a front elevational view thereof; and,

FIG. 4 shows a left elevational view thereof, with the right elevational view being a mirror image of the left elevational view of FIG. 4.

1 Claim, 1 Drawing Sheet

FIG. 1

FIG. 4

FIG. 2

FIG. 3
